UNITED STATES PATENT OFFICE.

CHARLES A. CARSCADIN AND GEORGE A. WOODMAN, OF CHICAGO, ILLINOIS,
ASSIGNORS OF ONE-THIRD TO RAYMOND C. DUDLEY, OF CHICAGO, ILLINOIS.

UNCOUPLING DEVICE.

1.110,297.

Specification of Letters Patent.

Patented Sept. 8, 1914.

Application filed May 18, 1912. Serial No. 698,129.

To all whom it may concern:

Be it known that we, CHARLES A. CARSCADIN and GEORGE A. WOODMAN, citizens of the United States, both residing at Chicago, in the county of Cook and State of Illinois, have jointly invented certain new and useful Improvements in Uncoupling Devices, of which the following is a specification.

10 Our invention relates to improvements in uncoupling devices of that class which are mounted on railway cars so that they can be operated to release the locking device of a coupler without requiring the brakeman to 15 go between the cars.

One of the objects of the invention is to provide an uncoupling device of simple construction, comprising only a few parts which are assembled in a novel manner to prevent 20 the surreptitious removal thereof and yet permit a separation of parts without damage to the device if the coupler head is accidentally pulled away from the car body.

Heretofore the railroad companies have 25 suffered considerable annoyance and expense by reason of the theft of parts of the uncoupling devices, and this is particularly true when those devices are used which comprise links and clevises secured by cotter pins or similar means. When the uncoupling device is rendered useless in this manner it becomes necessary for the brakeman to enter between the cars to couple or uncouple them, which involves great risk. Another 30 disadvantage of the uncoupling devices heretofore used is that they are so assembled and connected with the locking device that the coupler or locking device cannot be removed from the car without disconnecting 35 the uncoupling device also, and if the coupler should be accidentally pulled away from the car or out of its normal position the uncoupling device or its fastenings 40 would be broken.

45 Our invention aims to overcome these and other disadvantages and to provide an uncoupling device of few parts of simple and inexpensive construction, which can be readily applied to a car and easily operated, and 50 which embodies a separable connection to avoid damage to the device in event of an accident to the coupler as above mentioned.

And a further object of the invention is to dispense with the use of parts which can be surreptitiously and easily removed without 55 removing the locking pin.

Further objects and advantages of our invention will be apparent as it is better understood from the following description which, taken in connection with the accompanying 60 drawings, illustrates preferred embodiments thereof.

On the drawings:—Figure 1 is a top plan view of a portion of a car and coupler provided with an uncoupling device made in 65 pursuance of our invention; Fig. 2 is a front elevation of the device shown in Fig. 1 with parts broken away; Fig. 3 is an end elevation looking toward the right of Fig. 2; Fig. 4 is a side elevation of a slightly modified form of the hook and sleeve member shown partly in section; Fig. 5 is an end elevation looking toward the right of Fig. 4; Fig. 6 is a side elevation of another modified form of the device shown partly in section; 70 Fig. 7 is a vertical sectional view of the modified form shown in Fig. 6; Fig. 8 is a top plan view of still another form of the device in position upon a car; Fig. 9 is a front elevation of the device shown in Fig. 8 75 with parts broken away; Fig. 10 is an end elevation partially in section of the modified form of the invention shown in Figs. 8 and 9, the locking pin of the coupler being in lock-set position; Fig. 11 is a transverse vertical sectional view of the sleeve member 80 showing the position of the end of the hook when the locking pin of the coupler is in lock-set position; and Fig. 12 is a horizontal sectional view taken on the line 12—12 of 85 90 Fig. 11.

On the drawings 10 designates a coupler, which may be of any type, having a locking pin 11, and mounted on a car 12.

The uncoupling device preferably comprises two members 13 and 14. The member 13 consists of a single metallic rod mounted in a substantially horizontal plane in brackets 15 fastened to the car body and having its ends bent at right angles to the main portion of the member and to each other to form the operating arm or handle 16 and lifting arm 17.

As shown in Figs. 1 to 3, the member 14

is composed of a hook 18 and a sleeve 19 rigidly secured together and preferably made integral. The axis of the sleeve 19 is disposed at or about right angles to the plane of the hook and is adapted to form a tubular guide and telescopic connection for the end of the arm 17 when the members are assembled and in position upon the car. The hook 18 is adapted to fit loosely within the eye of the locking pin and is constructed to provide a straight portion 20 upon which the locking pin may slide to the right or left as the coupler is moved from central position when the cars coupled together travel around a curve. The hook 18 terminates in an upwardly bent end 21 at the end of the straight portion 20 to prevent the hook from being inadvertently removed from the eye of the locking pin.

In Figs. 4 and 5 a hook member is shown wherein the sleeve 22 and hook 23 are not made integral but constitute separate parts pivotally connected together. Except for this difference these members are like the sleeve 19 and hook 18 shown in Figs. 1, 2 and 3, and hereinbefore described. The pivotal connection between these parts is established by providing upon the sleeve an integral ear 24 having an aperture 25 therein in which an end 26 of the hook is inserted, the other end 27 of the hook being adapted to be inserted within the eye of the locking pin.

In Figs. 7 and 8 an embodiment of the invention is disclosed wherein the sleeve is provided upon the lifting arm 28 of the member secured to the car end. To this end the arm is made hollow and is provided with a slot 29 extending longitudinally thereof from the outer end of the arm inwardly a sufficient distance to permit a cylindrical element 30, which is loosely fitted within the hollow arm and upon which is formed the ear 31 extending through the slot, to slide longitudinally of the arm the required distance when the arm is moved to raise and lower the locking pin of the coupler. In this embodiment, however, instead of using a hook member to connect the locking pin of the coupler to the member secured to the car end I provide a link 32 which passes through the eye of the locking pin 11 and through an aperture 33 in the ear 31 of the member 30.

In the embodiment of the invention shown in Figs. 8 and 12 the sleeve 34 is provided with a hollow boss 35 extending outwardly at right angles to the axis of the sleeve and preferably located adjacent its outer end. The sleeve 34 fits slidably upon the operating arm 17 of the member 13 in the manner described in connection with the sleeve 14 in the embodiment of the invention shown in Figs. 1 and 3 and the sleeve 22 in the embodiment shown in Figs. 4 and 5. The hollow

boss 35 is provided at its base with the shoulder 36 which is disposed about the interior of the boss and which has recesses 37 formed therein, preferably upon opposite sides of a diameter parallel to the axis of the sleeve 34 and with an upwardly extending rib 42 disposed on each side of each recess. The hook member 38 has an end which fits loosely within the boss 35 and which is provided with a pair of outwardly disposed lugs 39 which when the parts are in operative position are disposed above the shoulder 36 and prevent the removal of the end of the hook from the boss. These lugs are preferably disposed in the same plane with the straight portion of the hook 41 upon which the locking pin of the coupler is adapted to be slidably mounted. The hook 38 is positioned within the boss 35 of the sleeve by inserting the lugs 39 through the recesses 37 of the shoulder, moving the end inwardly until the lugs clear the top of the ribs 42 and turning it through an angle of 90° and permitting it to fall into operative position as shown on the drawings. The parts are so constructed that when the locking pin is in lock-set position the end of the hook within the boss extends a substantial distance above the base of the boss, providing thereby a slidable connection between the sleeve and hook member which will permit the member 13 to assume its normal position when the locking pin is in lock set position so that the pin may drop to locking position without changing the position of the member 13. It is apparent that in thus connecting the hook and sleeve members a limited movement is permitted at all times therebetween and that a flexible and efficient connection is established.

The operation of the several embodiments of the invention hereinbefore disclosed is substantially the same, and the description of the operation of one of them will apply to the others.

When it is desired to uncouple a car provided with an uncoupling device made in pursuance of our invention the handle 16 may be raised, thereby elevating the operating arm and lifting the locking pin 11 by means of the member 14. The sliding connection between the arm 17 and the sleeve 19 of the member 14 will permit this pin to be raised substantially vertically, thereby preventing the pin from binding in the aperture of the coupler casting.

It will be manifest from the foregoing that the sliding connection between the two members of the uncoupling device provides for that freedom of movement therebetween which is essential to correspond with the longitudinal movement of the coupler in service.

It will also be apparent that should the coupler be pulled from the car body the

sleeve 19 of the member 14 will be pulled off the arm 17 of the member 13 so that neither member will be damaged and the member 13 will not be torn from the car body.

It will be obvious that various changes may be made in the form and construction of the parts and their arrangement without departing from the spirit and scope of our invention, or sacrificing any of its benefits, the forms hereinbefore described being merely preferred embodiments thereof.

We claim:—

1. An uncoupling device for railway cars comprising a section having an arm substantially extending outwardly horizontally therefrom, the said section being adapted to be secured to a car to dispose the said arm above the locking pin of the coupler, and a section adapted to freely telescope with the said arm and having an element depending therefrom beneath the telescopic connection between said arm and section adapted to be attached to the locking pin of the coupler, the telescopic connection between the said sections being of sufficient length to prevent removal of the parts of the device without removal of the device from the car or the locking pin from the coupler and permitting the said sections to be disconnected should the drawbar or coupler be pulled from the car.

2. An uncoupling device for railway cars comprising an operating rod adapted to be secured to a car and having an arm extending outwardly at substantially right angles to the body portion of the rod, a sleeve engaging said arm and freely movable thereon, and an element connected to said sleeve beneath its engagement with said arm and connecting said sleeve to the locking pin of the coupler and preventing removal of the sleeve from said arm when the parts are operatively arranged upon a car.

3. An uncoupling device for railway cars comprising an operating rod adapted to be secured to a car and having an arm extending outwardly at substantially right angles to the body portion of the rod, a sleeve engaging said arm and freely movable thereon, and a rigid member connected to said sleeve beneath its engagement with said arm and connecting said sleeve and the locking pin of the coupler and preventing removal of the sleeve from said arm when the parts are operatively arranged upon a car.

4. An uncoupling device for railway cars comprising an operating rod adapted to be secured to a car and having an arm extending outwardly at substantially right angles to the body portion of the rod, a sleeve embracing said arm and freely movable thereon, and an element slidably engaging said sleeve and connecting it to the locking pin of the coupler and preventing removal of

the sleeve from said arm when the parts are operatively arranged upon a car.

5. An uncoupling device for railway cars comprising a rod having an arm bent outwardly substantially horizontally at right angles thereto, said rod being adapted to be secured to a car to dispose said arm over the locking pin of the coupler, a sleeve loosely engaging said arm over said locking pin and freely movable on said arm, and a hook pivotally connected to said sleeve beneath the engagement of said sleeve and arm to depend beneath said sleeve and engage with the locking pin of the coupler when the parts are operatively positioned.

6. An uncoupling device for railway cars comprising a rod having an arm bent outwardly substantially horizontally at right angles thereto, the said rod being adapted to be secured to a car to dispose the said arm over the locking pin of the coupler, a sleeve adapted to loosely embrace the said arm above said locking pin, and a hook pivotally connected to said sleeve to depend beneath said arm when the parts are operatively positioned, said hook having a straight portion adapted to slidably fit with in the eye of the locking pin of the coupler to permit the locking pin to move horizontally as the cars travel around a curve.

7. An uncoupling device for railway cars comprising a rod adapted to be secured to a car and having an arm extending outwardly at right angles to the main portion of the rod, a sleeve adapted to loosely embrace the outwardly extending arm, and a hook slidably secured to the said sleeve, said hook being adapted to be attached to the locking pin of the coupler.

8. An uncoupling device for railway cars comprising a rod adapted to be secured to a car end and having an arm extending outwardly at right angles to the main portion of the rod, a sleeve adapted to loosely embrace the outwardly extending arm and provided with a hollow boss, and a hook having an end adapted to be slidably engaged with in the said boss, said hook being adapted for attachment to the locking pin of the coupler.

9. An uncoupling device for railway cars comprising a rod adapted to be secured to a car end and having an arm extending outwardly at right angles to the main portion of the rod, a sleeve fitted over the outwardly extending arm and having a downwardly depending hollow boss, a hook adapted to be secured to the locking pin of the coupler and having an end adapted to be slidably fitted within the said hollow boss of the sleeve, and means for retaining the end of said hook within the boss while the parts are in operative position.

10. An uncoupling device for railway cars comprising a rod having a lifting arm and adapted to be secured to a car, a sleeve fitted

on said lifting arm, and a hook having its ends bent at right angles to each other and connected by an inclined portion, said ends being disposed in substantially a single plane, one of said ends being adapted to be secured to said sleeve and the other to be slidably secured within the locking pin of the coupler.

11. An uncoupling device for railway cars comprising a rod having a lifting arm and adapted to be secured to a car, a sleeve fitted over said lifting arm, said sleeve being provided with a downwardly depending hollow boss having an inwardly extending recessed shoulder and guiding ribs extending upwardly within the boss, and a hook adapted to be attached to the locking pin of the coupler and having an end adapted to be inserted within the hollow boss of the sleeve, said end being provided with a plurality of lugs adapted to pass through the recesses and between the ribs when the parts are assembled and to be engaged by the shoulder

when the device is operated to lift the hook and locking pin of the coupler.

12. An uncoupling device for railway cars comprising a rod adapted to be secured to a car and having an arm extending outwardly from the car, a member adapted to engage the locking pin of the coupler, and a sleeve adapted to be telescopically connected with both the outwardly extending arm of the rod and the member adapted to engage the locking pin.

13. An uncoupling device for railway cars comprising a rod adapted to be secured to a car, a member adapted to engage the locking pin of the coupler, and a sleeve adapted to telescopically engage both the said rod and the said member to slidably connect them substantially at right angles to each other.
